FIRE EXTINGUISHER

Filed Jan. 23, 1946

Patented Dec. 18, 1951. Inventor, Lawrence H. Smith; assignor to Victor M. Langsett, both of Chicago, Ill. Filed Jan. 23, 1946. Serial No. 642,843. This application is a continuation-in-part of my application, Serial No. 630,333, filed Jan. 23, 1945, now abandoned.

My present invention relates to improvements in fire extinguishers, and more particularly to improvements in portable fire extinguishers of the so-called fog type.

UNITED STATES PATENT OFFICE

2,579,100

FIRE EXTINGUISHER

Lawrence H. Smith, Chicago, Ill., assignor to Victor M. Langsett, Chicago, Ill., as trustee

Application January 23, 1946, Serial No. 642,843

2 Claims. (Cl. 169—31)

1

This invention relates to fire extinguishers in general and in particular to portable fire extinguishers of the so-called fog type.

An important object of the present invention is the provision of a new and improved fire extinguisher having arranged therein a diaphragm, or other like structure, adapted to receive a predetermined quantity of pressure forming material, such as carbon dioxide; the body of the extinguisher being adapted to be filled with liquid, such as water, against which a pressure created by the expandable diaphragm is adapted to be exerted.

Another important object of the invention is the provision of new and improved means for filling a fire extinguisher casing with fluid, such as water, "Prestone" or the like, to be discharged from the extinguisher in a spray-like or fog-like fashion, there being an improved pumping means for pumping fluid into the container against the action of the pressure therein.

Another object of the invention resides in the construction and arrangement of the parts located in particular positions whereby the diaphragm structure of the device may be filled readily with suitable material, such as carbon dioxide, the arrangement and construction of means for injecting fluid within the extinguisher casing and against the pressure therein, and the construction and arrangement of the various parts constituting the pumping means per se, as well as the inlets, outlets, valves, etc.

Numerous other objects and advantages will be apparent throughout the progress of the following specification.

The accompanying drawing illustrates a selected embodiment of the invention and the views therein are as follows:

Fig. 1 is a detail sectional view taken longitudinally through the improved extinguisher;

Fig. 2 is a detail end elevational view of the right hand end of the extinguisher shown in Fig. 1;

Fig. 3 is a detail sectional view on the line 3—3 of Fig. 2;

Fig. 4 is a detail vertical section of the lower end of the piston which is arranged in its cooperating cylinder; and

Fig. 5 is a detail transverse sectional view taken on line 5—5 of Fig. 4 and showing the valve arrangement at the lower end of the piston.

The particular construction herein shown for the purpose of illustrating the invention comprises a body 1 which is preferably circular in cross section, although it may be made in any shape desired.

2

The body 1 preferably consists of an elongated hollow tube preferably of metal, one end of which is closed by an end closure cap 2. The cap 2 is secured in place by fastening means 3, such as bolts and nuts, to an annular flange 4 which is formed on an end of the body 1. The end cap 2 is preferably provided with an annular recess or groove 5 which cooperates with a similar annular recess or groove 6 in the annular flange 4, whereby there is formed a seat to receive that part of the reinforced end of a diaphragm 7 which terminates in an annular bead 8. The end cap 2 has an opening 9 provided therein, which opening is preferably concentric with the tubular body 1, the opening 9 being adapted to be closed by a closure 10.

The closure 10 is so constructed as to have gas-tight engagement with the material of the end cap surrounding the opening 9. The closure 10 may be maintained in position by the pressure within the diaphragm 7. The diaphragm 7 is adapted to receive expandable material, such as carbon dioxide (CO₂), such as through the opening 9, the closure 10 being unseated for that purpose and so as to create a pressure within the diaphragm and to expand the diaphragm. The diaphragm 7 is made of any suitable expandible rubber or rubber-like material. The end of the diaphragm may have a protecting end cap 11 for engagement with the inside of an opposed end cap 12 when the diaphragm is fully expanded so as to prevent damage to the diaphragm.

The end cap 12 is provided with a peripheral flange 13 which receives the end of the tubular body 1 and may be secured thereto in any convenient manner, such as by welding.

The end cap 12 has preferably formed exteriorly thereof a boss or boss-like structure 14 which forms a housing for a chamber 15. A piston 16 is arranged in the chamber 15 and has the same cross-sectional configuration as the chamber 15 so that the walls of the piston are in piston-cylinder contact. The chamber 15, which is preferably circular, provides a cylinder for the piston 16 which is adapted to be reciprocated in the chamber or cylinder 15.

The space 17 below the bottom of the piston 16 has communication with a passage 18 which leads into a passage 19 of larger diameter, the passage 19 having communication with the interior of the body 1.

A valve 20 is arranged in the passage or bore 19 whereby fluid entering the passage 18 from the space 17, is free to enter the casing chamber 21 within the body 1 but is prevented from back-

ing out of the chamber 21 through the passages 18 and 19.

The piston 16 is provided with a valve receiving chamber 22 in which there is mounted a loosely provided valve plate 23. Holes 24 extend through the base of the piston and are adapted to be closed operably by means of the valve plate 23. The bottom closure member 25a of the chamber 22 is also provided with a plurality of holes or elongated passages 25 which permit fluid to pass into the cylinder chamber 15.

A plurality of scalloped holes or openings 24a are formed in the periphery of the valve plate and are positioned in alignment with the holes 25. The valve receiving chamber 22, to receive the valve plate 23, may be formed in any suitable manner, such as by means of a member 25a, screwed upon the lower end of the piston 16.

An arm 26 is pivotally connected at 27 to the piston and extends upwardly through an opening 28 in the top of the boss 14. The upper end of the arm 26 is pivotally connected at 29 to a lever 30. The lever 30 is pivotally mounted as at 31 to projecting ears 32 formed rigidly on the flange 13 of the enclosure cap 12. The lever 30 extends forwardly into a handle portion 33 which terminates into a ball operating knob 34.

Another fluid inlet for the device comprises a plurality of spaced holes 35, Figs. 1 and 2, whereby fluid is adapted to be drawn into the chamber or cylinder 15. An outlet consisting of a threaded opening 36 in a boss-like projection 37, Fig. 3, is adapted to have a suitable discharge valve attached thereto or, if desired, a hose connection to which the nozzle (not shown) may be attached. Several openings 36a through the wall of the end plate may comprise the discharge outlet as shown in Fig. 3.

The end of the device is adapted to be inserted in a container having water, "Prestone," or other like material, whereby the inlet openings 35 will be covered by the liquid. The handle 33 when moved upwardly will cause the piston 16 to be forced downwardly, whereupon the valve 23 will seal the openings 24 and cause the liquid in the chamber 15 to be forced through the passage 18, the passage 19, and into the container or chamber part of the housing 1.

When the handle 33 is moved from raised to lowered position, there will be a suction created in the cylinder 15 whereby liquid will be sucked into the openings 35, when the handle is in lowered position, to fill the chamber 15 below the piston. When the handle 33 is again raised, the liquid, which is sucked in through the openings 35, and that which also passes through the openings 24, about the scalloped openings 24a at the periphery of the valve plate 23, and through the passages 25, will again be forced through the passages 18 and 19.

The valve disc 23 permits the piston to be easily reciprocated without any undue pressure and at the same time prevents any fluid in the cylinder 15 from passing out through the openings 24 and 25 during the pressure stroke. When the handle 33 is raised, the piston moves downwardly whereupon the valve disc 23 will cover the openings 24 and prevent any fluid from passing out through the openings 24. When the handle 33 is lowered and the piston is drawn upwardly, the valve disc 23 still permits easy operation of the piston.

The disc 23, therefore, prevents the fluid from passing out through the holes 24 during the pressure stroke and, during the suction stroke, per-

mits fluid to pass through the openings 24, recess 22, around the disc 23 and through the holes 25 into the chamber 15. The piston on its downward stroke, when the handle 33 is raised, will cause the inlet openings 24 to be closed, whereupon the trapped fluid in the chamber 17 will be forced through the passages 18 and 19 into the interior of the tubular body 1.

The raising of the piston permits fluid to pass into the chamber 15. The piston is adapted to be raised easily because of the looseness of the plate or disc 23 in the chamber 22. The scalloped openings 24a in the valve disc 23 coincide with the openings 25, thereby leaving a free flow during the raising of the piston. The center part of the valve disc, however, is solid and covers the openings 24 during the downward or pressure stroke of the piston to prevent fluid in the chamber 15 from passing out through the holes 24 (Figs. 4 and 5).

The plate 10 in the end closure cap 2 is adapted to have a pressure relief valve 38 mounted therein, as clearly shown in Fig. 1, whereupon any excess pressure in the diaphragm 7 will be relieved because of the relief valve 38.

An end handle 39 may be secured to the closing plate 10, as clearly shown in Fig. 1, whereby the device may be easily carried. Also a locking latch structure 40 secured to the top of the casting may be used for locking the handle 33 in its lowermost position so that a part of the handle 33 may be used for transporting the device from one location to another.

The invention provides a fire extinguisher which is preferably of the portable type and adapted to be moved easily from one position to another. The device is strong and durable in construction so that it may contain relatively high pressures for spraying liquid in fog-like fashion through the outlet nozzle mounted in the outlet opening 36 in the boss 37.

The pressure created in the chamber 21 by the compressed carbon dioxide in the diaphragm creates a pressure within the container 1 so that when a nozzle, (not shown) that is attached to the opening 36, and which nozzle is of any suitable construction is opened, a fog-like spray will be ejected therethrough under considerable pressure. Refilling of the chamber 21 is caused by immersing the end of the extinguisher in the liquid and then reciprocating the piston 16 by a pumping action on the handle 33. The device is adapted to be moved about from one position to another as it is relatively light in weight.

The pressure created in the diaphragm 7 by the compressed carbon dioxide will be relieved should the pressure become excessive, there being a safety pressure valve 38 for this purpose. Also, a pressure gauge 41 may be provided to indicate the pressure in the diaphragm 7. The gauge 41 may have threaded engagement with an opening 42 formed in the end plate or cap 2.

Changes may be made in the form, construction and arrangement of the parts without departing from the spirit of the invention or sacrificing any of the advantages thereof, and the right is hereby reserved to make all such changes as fairly fall within the scope of the following claims.

70 The invention is hereby claimed as follows:

1. In a fire extinguisher embodying a casing forming a fluid containing chamber from which a first fluid is discharged under pressure by means of a second fluid forced into the casing in out-of-commingling relation with the first fluid therein,

the combination comprising means carried by the casing and forming a cylinder having communication with the fluid containing chamber, a piston reciprocable in the cylinder, means to reciprocate the piston, fluid inlet means leading to the cylinder, said piston having a valve receiving chamber therein provided with openings in opposite walls thereof to permit fluid to pass through the piston, one of the walls of the last said chamber being removable, and a floating disc valve in the valve receiving chamber closing those of said openings in the other wall of the last said chamber which when the piston moves in a predetermined direction forces said first fluid from the cylinder into the fluid containing chamber.

2. In a fire extinguisher embodying a casing forming a fluid containing chamber from which a first fluid is discharged under pressure by means of another fluid forced into the casing in out-of-commingling relation with the first said fluid therein, the combination comprising means carried by the casing and forming a cylinder, a piston reciprocable in said cylinder, means to reciprocate the piston, a passage leading from the cylinder to the interior of the casing, fluid inlet means leading to the cylinder, said piston having openings therethrough to permit the first said fluid to pass through the piston, and a valve member adapted to close said openings when said piston moves in one direction to force the first said

fluid from the cylinder into the chamber, said valve member comprising a disc having an imperforate center and notches in its periphery, the notches communicating with the openings in the piston during movement of the piston in the other direction, the imperforate part of the disc closing the openings in the piston upon reciprocation of the piston in the first mentioned direction and blocking communication between said notches and the openings in the piston.
